US0D1003870S

(12) **United States Design Patent** (10) **Patent No.:** **US D1,003,870 S**
(45) **Date of Patent:** **** Nov. 7, 2023**

(54) **SET OF EARPHONES AND CHARGING CASE**

(71) Applicant: **SHANXI JONTER INTELLIGENT TECHNOLOGY CO., LTD**, Yangquan (CN)

(72) Inventor: **Xiaohuai Wang**, Hengyang (CN)

(73) Assignee: **SHANXI JONTER INTELLIGENT TECHNOLOGY CO., LTD**, Yangquan (CN)

(**) Term: **15 Years**

(21) Appl. No.: **29/830,869**

(22) Filed: **Mar. 16, 2022**

(51) LOC (14) Cl. **14-01**

(52) U.S. Cl.

USPC **D14/223; D14/207**

(58) **Field of Classification Search**

USPC D14/223, 207, 205; D13/108; D3/294, D3/274, 201; D24/174; 128/864-866; D9/529, 651, 655, 566; D28/78-79, 85, D28/87; D11/89-90; 381/380-381

CPC H04R 1/10; H04R 25/00; H04R 25/02; H04R 1/1066; H04R 1/1016; H04R 5/033; H04R 5/0335; H04R 1/105; H04R 1/1058; H04R 1/1083; H04R 1/1091; H02J 7/0045; A61F 11/08; B65D 75/30

Primary Examiner — Paula Allen Greene

(57) **CLAIM**

The ornamental design for a set of earphones and charging case, as shown and described.

DESCRIPTION

FIG. 1 is a perspective view of earphones of a set of earphones and charging case, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a charging case of the set of earphones and charging case, shown separately for ease of illustration and in an open configuration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the set of earphones and charging case, shown in use with the earphones received in the charging case; and,

FIG. 18 is a perspective view of the charging case of the set of earphones and charging case, shown separately for ease of illustration and in a closed configuration.

The broken lines in the drawings depict portions of the set of earphones and charging case that form no part of the claimed design.
